REFRIGERATION

Ralph C. Osborn, North Canton, Ohio, assignor
to The Hoover Company, North Canton, Ohio

Application June 25, 1941, Serial No. 399,636

17 Claims. (Cl. 62—119.5)

This invention relates to the art of refrigeration and more particularly to a novel arrangement of a three-fluid absorption refrigerating machine with respect to a cabinet with which it is to be utilized.

It is universal practice in the art of three-fluid absorption refrigerating machines to support the apparatus on a heavy, cumbersome and rigid L-shaped metal frame which extends throughout the mechanism compartment customarily provided in the lower portion of the cabinet structure and up the rear walls thereof in that portion of the cabinet structure commonly designated as an air flue through which the cooling air for the absorber and condenser flows to an ultimate point of disposal at the top of the cabinet.

Due to the space requirements of the heavy frame and its cross bracing structure it has heretofore been necessary to allow a minimum depth of approximately five inches for the rear flue. This imposes very serious difficulties upon the designer of three-fluid absorption refrigerating machines because of the fact that the total depth of household kitchen appliances is strictly limited by universally recognized custom and it will not do to have one appliance project further from the wall than the standard depth within which other kitchen appliances are maintained. Previous constructions are also wasteful of material because they fail to utilize the inherent great mechanical strength of the refrigerating machine itself.

Due to the fact that the various parts of three-fluid absorption refrigerating machines must be constructed to withstand high pressures and to maintain very light gases at such high pressures, they inherently possess great mechanical strength, nevertheless in prior machines this great mechanical strength has not been utilized for the purpose of supporting or aiding in the supporting of the various parts of the apparatus. The heavy L-shaped frame customarily provided in prior machines adds greatly to the weight of an already heavy mechanism, thus increasing the cost and difficulty of handling and installation of the machine.

Accordingly, it is a principal object of the present invention to devise an absorption refrigerating machine in which the inherently great mechanical strength of the various parts thereof is efficiently utilized to aid in supporting the machine in which the depth of the rear flue is reduced to a figure not more than half the present minimum depth of the flue and in which the

framework provided to hold the various parts of the apparatus in their proper relative positions is greatly reduced in size, extent and weight.

It is a further object of the present invention to utilize certain inherently strong parts of the refrigerating machine such as the vertically extending gas heat exchanger structure and the vertically extending rectifier as the supporting framework of the entire mechanism.

10 It is a further object of the present invention to place certain bulky portions of the refrigerating mechanism in spaces formed by cutting unnecessary insulation off the rear corners of the cabinet in order to utilize space more efficiently and to reduce the depth of the rear air flue in the cabinet.

15 It is a further object of the present invention to provide refrigerator constructions designed for use with a three-fluid absorption refrigerating machine in which certain bulky portions of the apparatus, such as the gas heat exchanger and vertically extending waste products of combustion flue are completely within the outside dimensions of the walls of the storage compartment in a construction which does not necessitate the provision of recesses in the cabinet structure to provide for embedded parts of the apparatus and in an arrangement which does not impair the insulating qualities of the cabinet construction.

20 It is a further object of the invention to provide a refrigerating mechanism of the three-fluid absorption type in which the rear air flue is substantially eliminated and in which the condenser is supported in a narrow side air flue.

25 Other and further objects of the invention will become apparent as the description proceeds when the same is taken in connection with the accompanying drawings, in which:

30 Figure 1 is a rear elevational view of a refrigerating machine embodying the present invention;

35 Figure 2 is a partial sectional view taken along the line 2—2 of Figure 1 and looking in the direction of the arrows;

40 Figure 3 is a partial rear elevational view partly in section of a modified form of the invention;

45 Figure 4 is a sectional view taken along the lines 4—4 of Figure 3 and looking in the direction of the arrows;

50 Figure 5 is a partial side elevational view of the form of the invention illustrated in Figures 3 and 4, and

55 Figure 6 is a sectional view of a detail of construction.

Referring now to the drawings in detail and

first to Figure 1 thereof, there is disclosed an absorption refrigerating machine of the three-fluid type comprising a boiler B, an analyzer D, a vertically extending finned air cooled rectifier R, a tubular air cooled condenser C, an evaporator E, a vertically positioned multi-pass gas heat exchanger G, a slightly inclined air cooled tubular absorber A, a liquid heat exchanger L, a solution reservoir S, a circulating fan or gas pump F which is driven by an electrical motor M. These elements are connected by various conduits to form a plurality of gas and liquid circuits constituting a complete refrigerating machine.

The above described refrigerating mechanism will be charged with a suitable refrigerant, such as ammonia, an absorbent therefor, such as water, and a pressure equalizing medium which is inert with respect to the refrigerant and the absorbent, preferably a dense gas like nitrogen.

The boiler B will be provided with a suitable heater, such as a fuel burner or an electrical cartridge heater, not shown, for the purpose of heating the solution therein contained.

A control mechanism will also be provided for regulating the energization of the motor M and the boiler heater in order to regulate the operation of the system. A preferred type of control mechanism is disclosed in Patent No. 2,228,343 of Curtis C. Coons, dated January 14, 1941.

The application of heat to the solution in the boiler B liberates refrigerant vapor therefrom which passes upwardly through the analyzer D, conduit 11 and rectifier R to the upper portion of the condenser C in which it is liquefied by heat exchange with cooling air. The liquid refrigerant formed in the condenser is conveyed therefrom through a U-shaped conduit 12 into the gas supply conduit 13 which enters the bottom of the evaporator.

Inert gas is supplied to the bottom of the evaporator E from the circulating fan F under pressure through the conduit 14, the gas heat exchanger G and the conduit 13. The inert gas flows upwardly through the evaporator with sufficient pressure and velocity to circulate the liquid refrigerant through the evaporator as the liquid is evaporating into the gas to produce a refrigerating effect.

Though any desired type of evaporator may be utilized with the present invention, a preferred form is disclosed and claimed in application of Curtis C. Coons, Serial No. 386,394, filed April 2, 1941, now Patent No. 2,328,195 granted Aug. 31, 1943.

The inert gas after traversing the evaporator and the finned box-cooling conduit 16 thereof discharges through a conduit 17 to the gas heat exchanger from which it is conveyed by a conduit 18 to the bottom portion of the absorber A. The inert gas flows upwardly through the absorber in contact with absorption solution in a manner to be described hereinafter and flows from the top portion of the absorber to the suction side of the fan or gas pump F through a conduit 19, thus completing the inert gas circuit.

The condenser side of the U-shaped liquid discharge conduit 12 is vented by means of a conduit 20 to the gas discharge conduit 17 of the evaporator.

The lean solution formed in the boiler by the evolution of refrigerant vapor therefrom is conveyed from the boiler to the solution reservoir S by way of the conduit 22, the liquid heat exchanger L and the finned pre-cooling conduit 23.

The solution reservoir S is vented by means of a conduit 24 to the suction conduit 19 of the inert gas fan in order to subject the reservoir and that part of the lean solution circuit between the reservoir and boiler to the suction pressure of the apparatus. The lean solution is elevated from the solution reservoir into the upper portion of the absorber by means of a gas lift pump conduit 25 to which pumping gas is supplied by means of a conduit 26 connecting between the discharge conduit 14 of the fan and the conduit 25 below the liquid level normally therein maintained.

The lean solution flows downwardly through the absorber by gravity in counterflow relationship to the rich mixture of pressure equalizing medium and refrigerant vapor flowing upwardly therethrough. The solution absorbs refrigerant vapor and the resulting heat of absorption is rejected to cooling air flowing over the exterior finned walls of the absorber tubes. The rich solution formed in the absorber flows to the bottom portion thereof from which point it is conveyed to the analyzer D by way of the conduit 28, the liquid heat exchanger L, and conduit 29, thus completing the solution circuit.

The above described refrigerating apparatus is associated with a suitable cabinet structure 30 which includes an insulated refrigerating chamber 31 provided in the rear wall thereof with an opening indicated at 32. The cabinet structure also includes a mechanism compartment 33 underlying the insulated chamber 31. The cabinet structure as a whole rests upon a base frame structure 35 which, as is indicated in Figure 1, is open to allow free access of cooling air into the compartment 33.

The side wall plates 36 of the chamber 31 are extended rearwardly of the rear wall of the compartment to form a shallow vertically extending air flue 37 along the rear wall of the cabinet. It will be noted that the two rear corners of the cabinet structure are diagonally cut off by the diagonal walls 38 in order to form a pair of roughly triangular shaped pockets 39 which nevertheless lie within the extended dimensions of the rear plate of the rear wall of the cabinet and of the side plates 36 not including that part of the plates 36 extended rearwardly to form the flue 37.

The boiler-analyzer liquid heat exchanger, solution reservoir, absorber, motor and fan unit are positioned in the compartment 33 beneath the chamber 31 and forwardly of the flue 37, so that no part of the apparatus need extend beyond the rear edge of the extended side plates 36. The mechanism within the compartment 33 rests upon and is suitably secured to a square frame 41 made up of welded channel and angle irons. The boiler analyzer liquid heat exchanger assembly is encased in insulating material indicated generally at 42 and rests upon the frame 41. The other portions of the apparatus within the compartment 33 may be supported from various parts of the frame 41 by short welded supporting bars and by welds where the parts touch in a known manner; if desired, however, the rigidity of the system itself in connection with the frame structure to be described hereinafter furnishes sufficient support in most sizes of machines.

The frame 41 at its rear portion includes a pair of upstanding channel iron members 50 and 51. These members are welded at their lower ends to the base frame 41 and at their upper ends to the lower portion of the gas heat exchanger G.

and to a vertically extending flue pipe 52 for the boiler B. It will be understood that the flue pipe will connect to the flue 53 of the boiler and that the pipe extends to the top portion of the cabinet so as to discharge the waste products of combustion at a point where they will not interfere with cooling of the condenser.

The elements 50 and 51 are braced on the frame 41 by angularly positioned angle irons 59. The arrangement of the inclined angle irons 59 is illustrated in Figure 5. The arrangement of these elements in the structure of Figures 1 and 2 is identical with that of Figure 5. The braces 59 are welded at their lower and upper ends to the outer sides pieces of frame 41 and to the supports 50 and 51, respectively.

The flue 52 must necessarily be made of heavy material because of the materials which pass therethrough, therefore it is inherently strong enough to serve as a vertical frame member for the apparatus. The flue 52 is interiorly lined with an asbestos liner 49 to protect the same from the hot gases discharged by the boiler heater and to minimize condensation in the flue. The gas heat exchanger G is exteriorly wrapped with a layer 54 of material such as sponge rubber which will prevent condensation from forming on the exterior surface thereof which, in part, may be at a low temperature.

The condenser is supported directly from the vertically extending rectifier R which in turn is supported by the conduit 11 and boiler-analyzer assembly. The condenser is also supported by the conduits 20 and 12 which connect the same to the gas conduits 13 and 17.

A pair of channel irons 55 and 56 extend across the back wall of the cabinet structure and are welded at their ends to the gas heat exchanger G and to the waste products of combustion flue 52. An insulated closure panel element 60 is supported from the channel irons 55 and 56 by suitable bolt elements or the like 61. The evaporator and the box-cooling unit 16 are supported from the conduits 17 and 13 and are also supported by the closure element 60. A suitable gasket 62 is provided to seal the joints between the closure element 60 and the walls of the opening 32.

If desired, short supporting elements may be welded between the elements 55 and 56 and the gas conduits 17 and 13, respectively, adjacent the points at which the gas conduits turn inwardly into the closure element 60 to provide additional support for the evaporator.

From the above description it is believed to be readily apparent that the entire refrigerating mechanism is formed into a rigid whole and in which the inherent mechanical strength of various parts of the refrigerating mechanism is utilized to form the supporting frame therefor, as a result of which the present apparatus is materially lighter and simpler than prior constructions.

It is also apparent that the only elements of the refrigerating mechanism lying rearwardly of the plane of the rear space of the cabinet per se are the condenser, rectifier, supports 55 and 56, and certain connecting conduits, as a consequence of which the depth of the flue 37 need be only approximately one-half the flue depth necessary in prior machines. The space utilization is very efficient as the combined gas heat exchanger and support and the combined products of combustion flue and support are positioned in cut-away corners of the apparatus where they lie within the

normal extent of the side and rear walls of the cabinet structure per se and yet do not interfere with the insulating capacity of the cabinet as the insulation of the corner is normally far thicker than necessary. It is also apparent that with the exception of the condenser and rectifier and certain connecting conduits all portions of the apparatus are positioned within the horizontally projected area of the normal outer walls of the insulating compartment 31 either in cut away corners thereof as is the case of the gas heat exchanger and flue pipe or beneath the compartment 31 as is the case of the absorber, boiler assembly, and the motor circulator assembly.

In the manufacture of the above described refrigerating machine the entire refrigerating mechanism, the frame 41, the frame bars 50, 51, 55, 56 and 59, the panel 60 are assembled as a unitary whole and may be tested prior to assembly with the cabinet. After testing of the apparatus the same is slid into the cabinet structure from the rear thereof with the evaporator passing through the opening 32 and the panel 60 passing into and filling the opening 32. The frame 41 then rests upon the base plate 35 of the cabinet structure to which it may be secured by suitable bolts, not shown. The apparatus is then completely constructed.

It will be appreciated that the refrigerating mechanism per se comprises a generally U-shaped structure with one leg of the U constituting the forwardly projecting evaporator, the bight portion of the U constituting the frame bars 50 and 51, the gas heat exchanger G, the flue pipe, condenser and rectifier, and with the other leg of the U constituting the boiler, analyzer, liquid heat exchanger, absorber assembly which will project beneath the bottom wall of the cabinet 31 and directly beneath the evaporator E. This is a rigid assembly with a minimum of framework provided therefor which is distinct from normal elements of the refrigerating mechanism itself.

Referring now to Figures 3 to 5, there is illustrated a modified form of the invention. The refrigerating mechanism per se of this form of the invention is identical with the refrigerating mechanism per se of the form of the invention described and illustrated in connection with Figures 1 and 2. The arrangement of the mechanism with respect to the cabinet, however, in this form of the invention is different from that disclosed in connection with Figures 1 and 2. Certain portions of the apparatus illustrated in Figures 3 to 5 being identical with portions of the apparatus described in connection with Figures 1 and 2, they are given the same reference characters primed.

In this form of the invention the mechanism chamber 33' and its associated parts are identical with those described and illustrated in connection with Figures 1 and 2. In this form of the invention however, the rear flue 80 which is formed by extending the left hand, as viewed in Figure 4, side wall 81 of the chamber 31' and by an auxiliary wall 82 positioned in spaced relationship with the right hand, as viewed in Figure 4, wall of the chamber 31' extends beyond the rear face of the rear wall of the chamber 31' only a distance sufficient to encase the conduits 12', 13', 17', 20' and the channel bars 55' and 56'; that is, a distance of approximately one-fifth of that customarily provided in the rear flue of three-fluid absorption refrigerating machines. As is readily apparent from Figure 4 the position of the gas heat exchanger G' is identical with the

position of the gas heat exchanger G shown in Figure 2. In this form of the invention, however, the wall 82 which is positioned in spaced relationship with one side wall of the cabinet 31' forms an additional cooling air flue 85 which receives the condenser C'. The waste products of combustion flue pipe 52' is positioned rearwardly in the flue 85 and inwardly of the plane of the rear face of the rear wall of the chamber 31'. The rectifier R' extends vertically between the condenser and flue pipe 52'.

The upper end of the flue 85 is closed by an extension 83 of the wall 82 which is provided with louvres 84 to allow escape of cooling air and waste products of combustion. In this form of the invention the condenser C' is additionally supported by a compression member 86 which is welded between one part of the bottom tube of the condenser C' and the rectifier R' below the level of the condenser. The rectifier is rigidly attached to the flue pipe 52' by a short compression member 87 and by a short tension member 88, thus forming a rigid assembly of the flue pipe, condenser and rectifier.

It is therefore readily apparent that in this form of the invention the rear flue is substantially eliminated except for a very shallow space required to relieve the conduits 13' and 17', but this is amply sufficient to convey away the cooling air which has passed across the absorber in the compartment 33', though the compartment 33' is also open to the flue 85 through which cooling air flows to pass across and cool the condenser C'. This form of the invention of course increases the space width of the cabinet but there are many circumstances in which this is unobjectionable and is much to be preferred to even a small increase in the depth of the cabinet due to a rear flue.

This form of the invention like that illustrated in Figures 1 and 2 is so constructed that the refrigerating mechanism forms a complete rigid assembly with the cooperation of the space frame elements and the channel bars 55' and 56'.

Both forms of the present invention provide very compact, simplified relatively light weight and extremely rigid assembly of refrigerating mechanisms in cabinets which are characterized by a great reduction in the depth of the cabinet structure and particularly in a reduction of that portion of the cabinet structure which is utilized to provide a rear air flue. It is also a characteristic of the present invention that the inherently great mechanical strength of the various parts of three-fluid absorption refrigerating machines is utilized most effectively to support the apparatus without the use of a complete additional framework.

While the invention has been described and illustrated in detail, various changes may be made in the arrangement, construction and proportion of parts without departing from the spirit of the invention or the scope of the appended claims.

I claim:

1. Three-fluid absorption refrigerating apparatus comprising an evaporator, a condenser, an absorber, a boiler and a vertically extending gas heat exchanger, a vertically extending waste products of combustion flue arranged to carry waste products from said boiler positioned in spaced relationship with said gas heat exchanger; a base frame element terminating below the level of said evaporator supporting said boiler; frame elements rigidly connecting said base frame to

the lower portions of said gas heat exchanger and said flue; connections constructed of strong tubing for conducting fluids between parts of said refrigerating apparatus and for suspending said evaporator, said absorber and said condenser from said gas heat exchanger, and frame elements rigidly connecting the upper portions of said gas heat exchanger and said flue.

2. In a refrigerator; a cabinet structure having an insulated refrigerating chamber and a mechanism compartment extending below and along a vertical wall of said refrigerating chamber; an absorption refrigerating mechanism associated with said cabinet structure comprising an evaporator positioned in said chamber, an air cooled absorber positioned in said compartment below said evaporator, a condenser positioned along said vertical wall adjacent the top thereof, a boiler positioned in said compartment, a gas heat exchanger extending vertically along a wall of said chamber; a boiler flue extending vertically along said wall of said chamber in spaced relationship with said gas heat exchanger; a base frame in said compartment below said refrigerating chamber supporting said boiler, and the lower ends of said gas heat exchanger and said flue; and connections for said refrigerating mechanism constructed of heavy tubing; said apparatus being so constructed and arranged that said absorber, said condenser and said evaporator are supported in their respective positions solely by said gas heat exchanger and said boiler flue.

3. In a refrigerator; a cabinet structure having an insulated refrigerating chamber and an underlying mechanism compartment; said cabinet structure having the rear vertical corners of said chamber cut away; an absorption refrigerating apparatus associated with said cabinet structure comprising an evaporator in said refrigerating chamber, an absorber and a boiler in said compartment, a condenser positioned adjacent a vertical wall of said chamber, a gas heat exchanger positioned in the space provided in one of said cut away portions of said cabinet and within the extended dimensions of the outer walls of said chamber and means connecting said evaporator, said absorber, said condenser, said gas heat exchanger and said boiler in circuit; a waste products of combustion flue for said boiler positioned in the other of said cut away portions and within the extended dimensions of the outer walls of said cabinet; and means including said connecting means for supporting said evaporator, said condenser and said absorber from said boiler, said gas heat exchanger and said flue.

4. In a refrigerator; a cabinet structure having an insulated refrigerating chamber and an underlying mechanism compartment; said cabinet structure having the rear vertical corners of said chamber cut away; an absorption refrigerating apparatus associated with said cabinet structure comprising an evaporator, an absorber, a boiler, a condenser and a gas heat exchanger connected in circuit; a frame in said mechanism compartment supporting said boiler and said gas heat exchanger, a products of combustion flue for said boiler in said cut away portions of said cabinet structure; said evaporator being positioned in said refrigerating chamber, said absorber being positioned in said mechanism compartment, said condenser being positioned closely adjacent a vertical wall of said chamber; said apparatus being so constructed and arranged that said absorber, said evaporator and said condenser are

supported by said gas heat exchanger and said flue.

5. A rigid refrigerating machine assembly comprising a tubular air cooled condenser; a tubular air cooled absorber; an evaporator; a boiler; a vertically extending gas heat exchanger, positioned adjacent a lateral end of said absorber; substantially rigid means connecting said condenser, said absorber, said evaporator, said gas heat exchanger and said boiler in circuit with said evaporator projecting forwardly of said condenser and said absorber lying below and in spaced relationship with said evaporator, a waste products of combustion flue extending vertically from said boiler adjacent the other lateral edge of said absorber and a base frame element secured to and supporting said boiler and the lower ends of said gas heat exchanger and said flue, said apparatus being so constructed and arranged that a rigid assembly is formed in which the absorber, condenser, evaporator, boiler and gas heat exchanger are secured to and supported from one another by said substantially rigid connecting means, and means rigidly connecting the upper ends of said gas heat exchanger and said flue whereby said base frame, said gas heat exchanger and said flue and said last mentioned means form the bottom, sides and top respectively, of a frame carrying said condenser and said evaporator above said base frame.

6. In a rigid refrigerating machine assembly; a plurality of refrigerator elements including a tubular air cooled absorber, a tubular air cooled condenser, a boiler assembly, an upstanding gas heat exchanger, an evaporator and conduit means connecting said elements in circuit; a base frame structure terminating below said evaporator and said condenser adjacent the lower end of said gas heat exchanger arranged to support said refrigerating apparatus in upright position, said base frame being secured to said boiler and the lower end of said gas heat exchanger; said apparatus being so constructed and arranged that said elements form a rigid self-supporting assembly characterized in that said absorber and said evaporator are positioned in vertically spaced relationship forwardly of said gas heat exchanger, and said condenser is positioned laterally of said evaporator and extends in the same general direction with respect to said gas heat exchanger.

7. In a refrigerator; a cabinet structure including an insulated food storage chamber having an opening in a wall thereof adapted to receive an evaporator, a closure element for said opening, a mechanism chamber underlying said storage chamber, means forming a shallow air flue along the vertical wall of said storage chamber having said opening, the corners of said storage compartment at said flue being rounded off to form spaces forwardly of said flue and within the confines of the walls of said storage compartment; a plurality of refrigerator elements associated with said cabinet structure comprising an evaporator positioned in said storage chamber, a condenser in said flue, an absorber in said mechanism chamber, a boiler in said mechanism chamber, inert gas conducting means positioned in one of said spaces, and conduit means connecting said elements and said inert gas conducting means in circuit; a waste products of combustion flue for said boiler lying in the other of said spaces; means in said mechanism compartment supporting said boiler, said gas conveying means, and said flue on the base of said cabinet struc-

ture; and means for supporting said closure element from said flue and said gas conveying means, said apparatus being so constructed and arranged that said refrigerator elements, said connecting means and said gas conveying means form a structural whole in which the various parts thereof are maintained in position by the inherent mechanical strength thereof.

8. In a refrigerator; a cabinet structure including an insulated food storage chamber having an opening in the rear wall thereof adapted to receive an evaporator, a closure element for said opening, a mechanism chamber underlying said storage chamber, means forming a shallow air flue along a vertical side wall of said storage chamber, the rear corners of said storage chamber being rounded off to provide spaces within the extended horizontal dimensions of the outer walls of said storage chamber; a plurality of refrigerator elements associated with said cabinet structure comprising an evaporator positioned in said storage chamber, a condenser in said flue, an absorber in said mechanism chamber, a boiler in said mechanism chamber, inert gas conducting means positioned in one of said spaces, and conduit means connecting said elements and said inert gas conducting means in circuit; a waste products of combustion flue for said boiler lying in the other of said spaces; means in said mechanism compartment supporting said boiler, said gas conveying means, and said flue on the base of said cabinet structure; and means for supporting said closure element from said flue and said gas conveying means, said apparatus being so constructed and arranged that said refrigerator elements, said connecting means and said gas conveying means form a structural whole in which the various parts thereof are maintained in position by the inherent mechanical strength thereof.

9. In a refrigerator, a cabinet structure including an insulated refrigerating chamber having an evaporator receiving opening in one wall thereof and a mechanism chamber having a portion underlying said refrigerating chamber and a shallow vertically extending portion; a refrigerating mechanism associated with said cabinet structure including an evaporator in said refrigerating chamber, an absorber and a boiler in the portion of said mechanism chamber underlying said refrigerating chamber and forwardly of the rear wall of said cabinet structure, a products of combustion flue for said boiler and a gas heat exchanger positioned in spaced relationship in the shallow portion of said mechanism chamber a condenser in the vertically extending portion of said mechanism chamber and closely adjacent the vertical rear wall of said refrigerating chamber; means connecting said evaporator, said condenser, said gas heat exchanger, said absorber and said boiler in circuit; means positioned wholly within said underlying portion of said mechanism chamber for supporting said apparatus on the base of said cabinet structure, said apparatus being characterized by the fact that said connecting means serves also to support said apparatus in position in said cabinet structure, a closure element for said opening and a light cross frame supporting said closure element and secured to said gas heat exchanger and said flue.

10. In a refrigerator; a cabinet structure having an insulated storage compartment, a mechanism chamber underlying said storage compart-

ment, a cooling chamber extending along a vertical side wall of said storage compartment, and a shallow chamber of sufficient depth to receive refrigerant conduit elements extending along the rear wall of said storage compartment, said storage compartment having a diagonally cut vertical rear corner on the side opposite to said cooling chamber; an absorption refrigerating apparatus associated with said cabinet structure including an evaporator in said storage compartment, an absorber and a boiler in said mechanism compartment, an air cooled condenser in said cooling chamber, a gas heat exchanger in the space formed by said vertically cut corner; and means lying in part in said shallow chamber for connecting said evaporator, said absorber, said boiler, said gas heat exchanger and said condenser in circuit.

11. In a refrigerator; a cabinet structure having an insulated storage compartment, a mechanism chamber underlying said storage compartment, a cooling chamber extending along a vertical side wall of said storage compartment, and a shallow chamber of sufficient depth to receive refrigerant conduit elements extending along the rear wall of said storage compartment, said storage compartment having a diagonally cut vertical rear corner on the side opposite to said cooling chamber; an absorption refrigerating apparatus associated with said cabinet structure including an evaporator in said storage compartment, an absorber and a boiler in said mechanism compartment, an air-cooled condenser in said cooling chamber, a gas heat exchanger in the space formed by said vertically cut corner; and means lying in part in said shallow chamber for connecting said evaporator, said absorber, said boiler, said gas heat exchanger and said condenser in circuit; a waste products of combustion flue for said boiler positioned in the rear part of said cooling chamber; means in said compartment supporting said boiler, said gas heat exchanger and said flue on said cabinet structure; said apparatus being so constructed and arranged that the same forms a rigid structure in which said connecting means serves to maintain the parts thereof in their proper relative positions.

12. In a refrigerator; a cabinet structure having an insulated storage compartment, a mechanism chamber underlying said storage compartment, a cooling chamber extending along a vertical side wall of said storage compartment, and a shallow chamber of sufficient depth to receive refrigerant conduit elements extending along the rear wall of said storage compartment, said storage compartment having a diagonally cut vertical rear corner on the side opposite to said cooling chamber; an absorption refrigerating apparatus associated with said cabinet structure including an evaporator in said storage compartment, an absorber and a boiler in said mechanism compartment, an air cooled condenser in said cooling chamber, a gas heat exchanger in the space formed by said vertically cut corner; a rectifier extending vertically from said boiler to said condenser and positioned in the rear portion of said cooling chamber, means lying in part in said shallow chamber for connecting said evaporator, said absorber, said boiler, said gas heat exchanger and said condenser in circuit, and a waste products of combustion flue for said boiler extending vertically in said cooling chamber, means bracing

said condenser and said rectifier from said flue; said apparatus being so constructed and arranged that the same forms a rigid structure in which the said connecting means serves to maintain the parts thereof in their proper relative positions.

13. A refrigerator assembly comprising a base frame element, a boiler resting upon and secured to said base frame element, a vertical gas heat exchanger positioned above and secured at its lower end to the upper end of said frame element, a vapor conducting element extending upwardly from said boiler, a condenser connected to the upper end of said vapor conduit and partially supported thereby, an evaporator positioned forwardly of said gas heat exchanger and said rectifier, gas conduits connecting said evaporator to said gas heat exchanger and supporting said evaporator, a conduit connecting said condenser to one of said gas conduits and also serving to support said condenser, an absorber and a gas pump positioned beneath said evaporator, gas conduits connecting said absorber and said gas pump to said gas heat exchanger and serving to support said absorber and said gas pump, a solution reservoir and a gas lift solution pump positioned below said absorber, and conduits connecting said boiler, said gas lift pump, said reservoir and said absorber to form a solution circuit, said assembly forming a substantially rigid structure in which the inherent strength of the parts thereof serves to maintain the same in their proper positions relative to each other and to support them from said base frame.

14. In a refrigerating apparatus of the absorption type, a boiler, an absorber, a condenser, an evaporator, an upstanding heat exchange element, means connecting said elements in circuit to form a refrigerating system, an upstanding products of combustion flue for said boiler, said heat exchange element and said products of combustion flue being spaced laterally at the rear corners of said refrigerating apparatus, said absorber being positioned forwardly of said gas heat exchanger, said evaporator being positioned above said absorber, said condenser being positioned laterally of said evaporator, a base frame secured to said boiler and the lower ends of said heat exchange element and said flue for supporting said apparatus in vertical positions, frame means rigidly connecting the upper portions of said heat exchange element and said flue to form therewith and with said base frame a rigid vertical supporting structure and conduit means for supporting said evaporator, said condenser and said absorber from said heat exchange element and said boiler.

15. In a rigid refrigerating machine assembly; a plurality of refrigerator elements including a tubular air cooled absorber, a tubular air cooled condenser, a boiler assembly, a vertically extending gas heat exchanger, an evaporator and conduit means connecting said elements in circuit, a vertically extending products of combustion flue, means positioned below said evaporator and said condenser supporting said boiler assembly and the lower ends of said gas heat exchanger and said products of combustion flue and a light cross frame connecting the upper ends of said gas heat exchanger and said flue; said apparatus being so constructed and arranged that said elements form a rigid self-supporting assembly characterized in that said absorber and said evaporator are positioned in vertically spaced relationship forwardly of said gas heat exchanger.

16. In a rigid refrigerating machine assembly; a plurality of refrigerator elements including a tubular air-cooled absorber, a tubular air-cooled condenser, a boiler assembly, a vertically extending gas heat exchanger, a fluid circulator, an evaporator and conduit means connecting said elements in circuit, a vertically extending products of combustion flue, means positioned below said evaporator and said condenser supporting said boiler assembly and the lower ends of said gas heat exchanger and said products of combustion flue and a light cross frame connecting the upper ends of said gas heat exchanger and said flue; said apparatus being so constructed and arranged that said elements form a rigid self-supporting assembly characterized in that said absorber and said evaporator are positioned in vertically spaced relationship forwardly of said gas heat exchanger.

17. In a rigid refrigerating machine assembly; a plurality of refrigerator elements including a tubular air-cooled absorber, a tubular air-cooled

condenser, a boiler assembly, a vertically extending gas heat exchanger the lower end of which is positioned adjacent a rear corner of said absorber, an evaporator and conduit means connecting said elements in circuit, a vertically extending products of combustion flue, the lower portion of which is positioned adjacent the other rear corner of said absorber, means supporting said boiler assembly and the lower ends of said gas heat exchanger and said products of combustion flue; and means connecting the upper ends of said gas heat exchanger and said flue and lying closely adjacent said condenser, said apparatus being so constructed and arranged that said elements form a rigid self-supporting assembly characterized in that said absorber lies in a plane inclined slightly to the horizontal and said evaporator and said absorber are positioned in vertically spaced relationship forwardly of said gas heat exchanger.
